(57) **CLAIM**

The ornamental design for a body panel for an automobile, as shown and described.

DESCRIPTION

FIG. 1 is a front perspective view of a body panel for an automobile of our new design;

FIG. 2 is a front view thereof;

FIG. 3 is a left side front view thereof;

FIG. 4 is a right side view thereof;

FIG. 5 is a top plan view thereof;

FIG. 6 is a bottom view thereof;

FIG. 7 is a rear view thereof; and,

FIG. 8 is a rear perspective view thereof.

Our design includes a mirror image of the embodiment depicted.
